PNEUMATIC HEEL

Bernard Rubel, New York, N. Y.

Application August 13, 1938, Serial No. 224,717

7 Claims. (Cl. 36—35)

The present invention relates to resilient heels or lifts for footwear, such as shoes, and more particularly to resilient heels having a hollow, cup-shaped insert of greater resiliency, whereby greater comfort and ease of walking on such heels is obtained, and to methods and molds for making such heels.

In Patent No. 2,145,994 issued to me February 7, 1939, I have described a resilient heel wherein the main body portion of the heel is provided with a recess in its tread surface within which is loosely and removably arranged, in dovetailed relation, a cup-shaped insert. Air is trapped within the insert to be slowly released between the recess wall and the surface of the insert when pressure is applied upon walking to the insert to thereby provide pneumatically resilient heel.

I have found that the heel described in said copending application may be improved by sealing the insert cup along its upper edge to the walls of the recess. The insert is thereby held in the recess in spaced relation to the walls thereof to permit its compression therein while walking, the air from the cup being gradually to some extent expelled intermediate the heel and the shoe to which it is attached.

The present invention, therefore, contemplates the provision of a heel having a main body portion provided with an opening in which a cup-shaped insert is arranged and secured at its edge to the inner edge of the opening, to thereby provide a shock absorbing member in the central portion of the heel and extending therebelow.

This invention contemplates still further the provision of heels of the character described wherein the insert is of a material which is of greater resilience than the main body portion and wherein the main body portion is provided with hollowed studs projecting from its tread surface to a point below the insert, whereby absorption of the walking impact is made gradual, being first taken up by the insert, then by the hollow studs and finally by the resilient body portion of the heel, thus increasing the comfort of the heel of the present invention to a maximum.

The foregoing, as well as many other advantages and superiorities of the resilient heels of the present invention, will become more apparent from one embodiment of such heel which is illustrated in the accompanying drawing, in which

Fig. 1 is a plan view of the outer, tread surface of the heel of the present invention;

Fig. 2 is a similar view of the inner surface thereof;

Fig. 3 is a longitudinal cross-sectional view thereof taken along line 3—3 of Fig. 2;

The main body portion 10 of the heel of the present invention is of the usual outline, and constructed, preferably, of the usual resilient hard vulcanized rubber commonly used for the purpose. It is provided with the usual peripherally arranged fastening nail or screw receiving recesses 12, each of which may be reenforced with the usual embedded perforated plates or washers 14.

The main body portion is provided with an opening 16 extending through the central portion thereof. Such opening may be of any desired outline, preferably of the general outline of the heel, and may be of relatively extensive area.

Arranged in the opening 16 and projecting therefrom on the tread side of the heel is an insert 18, preferably of a substance of relatively higher resilience than the main body portion 10.

In order to provide a maximum of comfort in walking, the insert member 18 is hollow or cup-shaped, with the cupped hollow 20 facing the inside of the heel so that air may be trapped therein between itself and the shoe heel surface to 25 which it is attached, to form a pneumatic cushion from which the air to some extent will slowly escape between the heel and the shoe.

The insert 18 is secured at its innermost edge, throughout the periphery thereof to the innermost edge of the opening 16.

To permit the full impression and collapse of the insert 18 under the impact of walking, it is arranged in the opening with its sides 22 spaced from the walls of the openings, thereby 35 providing the peripheral space 24 for the resilient expansion of the insert within the opening. Such construction also enhances the non-skid characteristics of the heel by allowing swaying room for the insert.

In order to reinforce the insert and, more particularly, to insure that it will not remain in collapsed state for a prolonged time after air is expelled therefrom through the space intermediate the heel and the shoe, as might result due to the fact that the pressure with which the heel is normally held against the shoe might prevent or retard the intake of air therebetween, I provide within the hollow of the insert one or more upstanding walls 26. Preferably, a plurality of such walls are provided, arranged in web formation to distribute their resilient effect throughout the insert. Preferably, also, such walls are of a height less than the depth of the hollow to per-

mit a relatively large degree of resilience for more ready compression.

It will be apparent that the walls 26 will accelerate the return of the insert to its normal shape 5 immediately after walking pressure is relieved by their resilient tendency to straighten out, thereby creating suction for the return of air into the insert hollow under vacuum.

Preferably, to obtain increased air cushioning 10 or pneumatic effects, the partitions may be arranged to form chambers, such as the circular chamber 28, where air may be further trapped to be slowly released and thus obtain increased cushioning.

15 The tread surface 19 of the insert preferably extends approximately $\frac{1}{8}$ of an inch below the tread surface 21 of the main body portion of the heel.

In association with the insert, the heel may be 20 provided with a plurality of studs 30 formed of the main body portion of the heel and preferably arranged peripherally about the insert, as intermediate the fastening recesses 12.

The studs 30 project slightly above the general 25 surface of the main body portion of the heel but to a lesser height than the projection of the insert 18, and their resilience may be increased by rendering them interiorly hollow, by providing the recesses 32 extending from the underside of 30 the heel into such studs, and by providing the annular grooves 34 sunk into the tread surface of the heel about the studs, thus rendering the studs of relatively greater resilience than the main body portion of the heel from which they are formed.

35 It will be apparent that the heel of the present invention is resilient, durable and economical, and that it possesses the further quality that its resilience is progressively decreased as it is trod on, resulting in the gradual increase of resistance 40 to tread pressure, thereby reducing the shock of walking. This results from the fact that, when treading on the heel, the furthest projecting relatively more resilient insert first meets the ground and is compressed against gradually increasing 45 resistance offered by the entrapped air and the supporting walls 26, until the pressure is taken up by the studs 30 which are of a less resilient material than the insert but are of a more resilient construction than the heel body 10 of which 50 they are a part, and these studs are mushroomed or depressed gradually, with increasing resistance, into the surrounding grooves 34, until the least resilient main body portion of the heel is trod on.

55 To enhance the ground gripping qualities of the heel of the present invention, its more resilient parts, such as the insert, and the studs, may be provided with ground-gripping treads 36, such as a diamond tread on the insert and the concentric circular tread on the studs. It will be apparent that these treads, in addition to the snubbing effect provided by the spaces 24 and 60 34 about the insert and studs, respectively, will increase the non-skid properties of the heels of the present invention.

65 While any means for securing the insert to the heels may be used, such as cementing or the like, I prefer to accomplish the same by molding the resilient main heel portion and the relatively 70 more resilient insert integrally, thereby obtaining maximum strength and durability.

This completes the description of one embodiment of the heel. As it is obvious that many modifications and variations may be made in the 75 embodiment described with the use of mere

mechanical skill and within the spirit and scope of my invention, it is to be understood that I desire to be protected for any such modifications and variations that are within the scope of the claims hereto appended.

5 I claim:

1. A heel for a shoe comprising a resilient body portion having a central opening and an insert of relatively greater resiliency arranged with the said opening, said insert being secured by the inner edge of its peripheral wall throughout its circumference to the inner edge of the wall of the said opening and arranged therein in spaced relation to its walls and projecting outwardly thereof, whereby the projecting insert portion 15 may dispose itself, when trod upon within the said space.

2. A heel for a shoe comprising a resilient body portion having a central opening and a substantially cup shaped insert of relatively greater resiliency arranged in spaced relation within the said opening, the said insert being secured by its edge throughout its circumference to the inner edge of the said opening, and projecting outwardly of the opening, whereby said insert, upon contact, 20 will be compressed within the said space to form an air pocket with the underside of a shoe.

3. A heel for a shoe comprising a resilient body portion having a central opening and a substantially cup-shaped insert of relatively greater resiliency arranged within the said opening to project outwardly thereof with its cavity facing the shoe contact ing surface, the said insert being secured at its inner edge, throughout its circumference, to the inner edge of the said opening, and 30 spaced therefrom throughout the remainder of its height, whereby air trapped within the said insert will be prevented from escaping through the said opening, the said insert being provided 35 interiorly with a web of upstanding walls where- 40 by it is prevented from remaining in collapsed state after pressure is removed.

4. A rubber heel comprising a resilient body member, a plurality of studs projecting from the tread side of said body member, said stud being 45 hollowed interiorly and provided with outer bounding grooves in the heel body surface, whereby said studs are rendered of relatively greater resilience than the main portion of the body member, said body member having a central 50 opening and a cup shaped insert of relatively greater resilience arranged within the said opening in spaced relation thereto and secured by its inner edge, throughout its circumference, to the inner edge of the opening, whereby air caught in 55 the insert cup is prevented from escaping through the said opening, the said insert projecting outwardly from the said opening beyond the said studs whereby the resilience is gradually diminished and the shock of walking gradually absorbed.

5. A rubber heel comprising a resilient body member, a plurality of studs projecting from the tread side of said body member, said stud being 65 hollowed interiorly and provided with outer bounding grooves in the heel body surface, whereby said studs are rendered of relatively greater resilience than the main portion of the body member, said body member having a central opening and a cup-shaped insert of relatively 70 greater resilience arranged within the said opening in spaced relation thereto and secured by its inner edge, throughout its circumference, to the inner edge of the opening, whereby air caught in the insert cup is prevented from escaping 75

through the said opening, the said insert projecting outwardly from the said opening beyond the said studs whereby the resilience is gradually diminished and the shock of walking gradually absorbed, the said insert being provided interiorly with an upstanding wall, whereby it is prevented from remaining in collapsed state after walking pressure is removed.

6. A rubber heel comprising a body portion having an opening arranged centrally thereof, and a cup-like member having a comparatively thin wall section arranged within the said opening and secured to the inner edges thereof at the upper edges of the cup wall, the walls of the cup-like member being arranged in spaced relation to the wall of the said opening and the convex por-

tion of the cup-like member extending below the said body portion.

7. A rubber heel comprising a body portion having an opening arranged centrally thereof, a cup-like member having a comparatively thin wall section arranged within the said opening and secured to the inner edges thereof at the upper edges of the cup wall, the walls of the cup-like member being arranged in spaced relation to the wall of the said opening and the convex portion of the cup-like member extending below the said body portion, and upstanding resilient walls formed in a web on the inner face of the convex portion of the cup-like member of a height less than the walls thereof.

BERNARD RUBEL.
